DESIGN FOR A PERFUME BOTTLE

Paul H. Ganz, New York, N. Y., assignor to D. Lisner & Co., New York, N. Y., a corporation of New York

Application November 15, 1934, Serial No. 54,016

Term of patent 14 years

To all whom it may concern:

Be it known that I, Paul H. Ganz, a citizen of the United States and a resident of the city, county, and State of New York, have invented a new, original, and ornamental Design for a Perfume Bottle, of which the following is a specification, reference being had to the accompanying drawing, forming part thereof.

Figure 1 is a view in perspective of a perfume bottle, showing my new design;

Figure 2 is a second perspective view thereof, at a different angle; and

Figure 3 is a plan view thereof.

The view of Figure 1 is taken at such an angle as to show one of the sides and one of the ends of the bottle, as well as the top, while the view of Figure 2 is more in the nature of an end elevation, in which one of the ends is foremost, while one of the sides is also visible, and the top is barely visible.

I claim:

The ornamental design for a perfume bottle, as shown and described.

PAUL H. GANZ.
